HARNESS STOP MOTION FOR LOOMS.

Application filed December 31, 1926. Serial No. 158,943.

This invention relates to loom stopping mechanism and is more particularly directed to means for stopping the loom on the occurrence of an abnormal condition in the harness mechanism.

During weaving the harness frames are raised and lowered through a train of mechanism associated with the harness frames by means of harness connectors, and should an abnormal condition occur in the harness mechanism, such, for instance, as the breakage or undue slackness of a harness connector, injury is liable to occur to the warp threads and imperfect cloth be produced. Attempts have heretofore been made to remedy this condition but the complications introduced by the trains of mechanism employed have rendered the adoption of such mechanisms as have heretofore been proposed objectionable.

One of the objects of the present invention is to provide a harness stop mechanism which will be simple in construction, effective in operation in stopping the loom upon the occurrence of a fault in the harness mechanism, and which will at the same time indicate to the weaver the cause of loom stoppage.

The invention and new combination of parts and novel features thereof will best be made clear from the following description and the accompanying drawings of one good practical form thereof.

In the drawings:

Fig. 1 is a perspective view with some of the parts broken away, showing a loom provided with the present invention;

Fig. 2 is an enlarged perspective detail showing more particularly the transversely movable detector bars and the stopping finger in its normal position during weaving;

Fig. 3 is a side elevation of the stopping mechanism looking from the rear of the loom and showing the stopping finger in its loom stopping position;

Fig. 4 is a cross-section on the line 4—4 of Fig. 3;

Fig. 5 is a side elevation showing the train of mechanism for knocking off the shipper when the transversely movable detectors, or one of them, is arrested; and

Fig. 6 is a diagrammatic view showing the stop finger actuator and harness connec-

tors by full lines in their normal condition 55 and by dotted lines showing the actuator 55 as having been depressed by a too slack harness connector.

In accordance with the present invention, the means for effecting loom stoppage upon the occurrence of an abnormal condition in the harness connectors is associated with a warp stop mechanism wherein transversely movable toothed detector bars are employed in connection with means for effecting loom stoppage when a fault occurs in a warp thread. The shedding mechanism for opening the warp for the insertion of a weft thread may be of any usual or desired type and the number of harnesses may be varied 60 in accordance with the character of cloth being woven, the essentials in this respect being that should an abnormal condition occur in any of the harness connectors, the loom will be brought to rest to enable the 65 loom attendant to correct the fault.

The loom frame 1 may be of usual construction and as shown is provided with risers 2, one at each side of the loom frame, which support the cross-beam or arch 3. 70 Pivotally mounted on the loom frame are the levers 4 constituting a part of a well-known type of shedding mechanism, and each of the levers 4 is operatively associated with a harness frame by means of connectors 5 which in the present instance are shown as secured to rocker arms 6. To each upper portion of the rocker arm 6 is secured a harness connector 7 which passes over 75 guide sheaves or pulleys 8 and leads downwardly to one of the harness frames 9. Similarly, the lower end portion of each rocker 6 has secured thereto a harness connector 10 which passes over a sheave or pulley 11 supported by the arch 3 and is secured to one of the harness frames 9. The levers 4 are herein shown as of the bell crank type, although they may be of any usual form of harness lever operating means, and the outwardly projecting arms 12 of each lever have secured thereto a harness connector 13 leading downwardly and passing around guide pulleys or sheaves 14 at the lower portion of the loom frame. The connectors 13 lead from the pulleys or 80 sheaves 14 horizontally, as indicated in Fig. 1, and pass around suitable guide sheaves or pulleys 15 at the lower part of the loom.

100
105

frame, then upwardly, as indicated in Fig. 1, and the upper end of each connector is secured to the lower end of a harness frame 9, the effect being that when the levers 4 are actuated by any of the well-known forms of shedding mechanism, the harnesses 9 will be raised or lowered to form the shed. There is nothing new in this feature, and the shedding mechanism as well as the means for actuating the harness frames may be varied indefinitely, as may also be the number of harness frames employed.

The warp threads *a* pass from the warp beam 16 over the whip roll 17 and from there pass into control of the harness frames, with the result that as the harness frames are raised or lowered by the shedding mechanism the warp threads will be appropriately moved to form the shed, and between the whip roll 17 and the harness frames is the warp stop motion.

The warp stop mechanism comprises the side brackets 18, one at each side of the loom, between which extend the transverse toothed detectors. In the present instance of the invention, each side frame 18 has secured thereto a fixed detector bar 19 having a series of teeth 20, and associated with each of the fixed detector bars 19 is a transversely movable detector bar 21 which is likewise provided with a series of teeth 22, as indicated in Figs. 2, 3 and 4. The fixed detector bars 19 are provided with the slots or openings 23 through which extend the pins 24 which are connected to the links 25 associated with means for imparting to the movable detector bars their transverse motion. In the present instance of the invention, the means for imparting transverse movement to the movable detector bars may be substantially similar to the construction shown and described in the patent to Harry A. Davis and Arthur S. Johnson, No. 1,538,625, dated May 19, 1925, except as modified in the respects hereinafter noted.

Mounted for rocking movement on one of the side frames or supports 18 is a rocker 26 to which rocking movement is imparted by an arm 27 connected at its free end portion to a rod 28 which extends downwardly and is actuated from the lower or cam shaft 29, the construction being such that as the cam shaft is actuated, the rocker 26 will have imparted thereto the desired rocking movement. Extending upwardly from the rocker 26 are the yielding fingers 30, each of which is pivotally connected at 31 to a link 25 associated with the transversely movable toothed detector. The fingers 30 and their association with the rocker 26 may be substantially the same as more fully described in the Davis and Johnson patent hereinbefore mentioned, the construction being such that as the rocker 26 is given its rocking movement, the associated fingers 30 will im-

part to the transversely movable detector bars their transverse movements.

Pivottally mounted on the rocker 26 at 32 are a series of actuators 33, one for each finger 30, and such actuators rest upon the cross-bar 34 carried by arms 35 pivotally mounted at 36 to the rocker. Each of the actuators 33 is connected at its inner end, as at 37, to a finger 30, with the result that should any one of the fingers 30 be arrested in its movement with the rocker, it will impart to its associated actuator 33 movement to cause the cross-bar 34 to be depressed. Extending downwardly from the bar 34 is the presser 38 which bears upon the end of a flexible member 39. The flexible member 39 is enclosed within a flexible sheath 40 and its end remote from the warp stop mechanism bears upon the plunger 41 adapted to lift the dog 42 into the path of a bunter 43 carried by the lay 44. The dog 42 is mounted for backward yielding movement under the action of the bunter 43, as more fully described in the Davis and Johnson patent, and is connected by a rod 45 to the shipper 90 knock-off 46, the construction being such that should the dog be raised into its operative position by one of the fingers 30, the loom will be stopped, substantially as more fully described in the Davis and Johnson 95 patent.

Extending between the side supports or brackets 18 of the warp stop mechanism is the rod 47 which may if desired be constituted as one of the warp supports, and mounted upon the rod 47 is the stop finger 48. In the present instance the stop finger 48 is shown as of light wire construction and has coils 49 which embrace the rod 47 between the collars 50 secured to the rod 47, so that the stop finger may have rocking movement upon the rod 47.

The stop finger 48 is thus associated with the toothed detector bars in position such that should the stop finger be lowered from its normal position it will engage between the teeth of the toothed detector bars and arrest movement of the movable detector bar, to thereby effect loom stoppage. The stop finger 48 is normally held in its upper 110 or inoperative position by suitable means with permissive movement into engagement with the teeth of the detector bars. In the present instance of the invention, the stop finger 48 has an arm 51 extending outwardly 115 from the rod 47, and is provided with a weight 52 which serves as a good practical form of means for normally holding the stop finger in its upper or inoperative position with respect to the teeth of the detector bars. 120

From the construction thus far described it will be obvious that the stop finger 48 normally projects upwardly above the toothed detector bars, and in such position serves as a signal or indicator to indicate to the loom 125

attendant that the harness connectors are in normal working condition, as will presently appear.

The stop finger 48 as shown has its end 5 portion provided with an eye 53 to which is secured a downwardly extending member 54 connected at its lower end to an actuator 55 which extends under the harness connectors 13, Fig. 1, and is pivotally mounted to the 10 loom frame, as at 56, the construction being such that should any one of the harness connectors above the actuator become slack and consequently rest upon the actuator, it will cause the stop finger 48 to be moved downwardly into locking engagement with the 15 teeth of the toothed detector bars, and, perforce, effect loom stoppage. It is convenient and preferred to carry the stop finger 48 above the entire series of toothed detector 20 bars, so that it may engage with the teeth of all of the bars when the stop finger is moved downwardly by too much slackness in a harness connector, but the invention is not necessarily limited to this detail because 25 it is quite sufficient if the detector bar in its downward movement by an abnormally conditioned harness connector should engage one of the series of detector bars and thereby stop the movement of the movable 30 detector bar. By carrying the detector finger across the entire series of toothed detector bars, it more obviously indicates to the loom attendant the cause of loom stoppage by the fact that the stop finger has 35 been moved downwardly.

Associated with the toothed detector bars are a series of drop wires, indicated at 57, which are normally supported by the warp threads during weaving, and should a warp 40 thread become abnormally conditioned, either by breakage or too much slackness therein, the associated drop wire will engage the toothed detector bars and arrest the movement of the transversely movable bar, 45 to effect loom stoppage.

Should any of the harness connectors between the shedding mechanism and harness frames become abnormally conditioned, as by breakage or too much slackness in any 50 part thereof, the portion of the harness connector extending over the actuator 55 will drop and rest upon the actuator, thereby moving the stop finger from its normal position into engagement with the toothed detector bars and effect loom stoppage, and the fact that the stop finger has been moved 55 from its normal position at once indicates to the loom attendant the cause of loom stoppage, thereby enabling him at once to remedy the fault in the harness connectors. Should a warp thread break or become too slack, and the loom be stopped, the stop finger will still maintain its upper position, thereby indicating to the loom attendant 60 that the harness connectors are in normal

working condition but that the loom has been stopped from a thread fault.

In positioning the stop finger for cooperation with the toothed detector bars, it should be located with respect to the teeth in the 70 fixed detector bar, so that when the stop finger is moved into loom stopping position, it will enter the recess between the teeth of the fixed detector bar and arrest movement of the transversely movable toothed detector bar by locking the two bars together. 75

The present invention provides a simple, effective, and readily observable means for indicating the cause of loom stoppage when any one of the harness connectors becomes 80 too slack for proper weaving purposes. 86

What is claimed is:

1. In a harness stop mechanism for looms, the combination of the shedding mechanism including harness connectors, a toothed detector member having a detecting movement in the direction of its length, a stop finger normally held out of engagement with the toothed detector member, means for effecting loom stoppage when the lengthwise movable 90 detector member is arrested in its detecting movement, and means for causing the stop member to engage a tooth of the detector member and arrest its lengthwise movement when an abnormal condition occurs in the 95 harness mechanism.

2. In a harness stop mechanism for looms, the combination of shedding mechanism including harness connectors, a detector having teeth, means for imparting lengthwise 100 detecting movements to the detector, means for effecting loom stoppage when the lengthwise movement of the detector is arrested, a stop finger, means normally acting to hold the stop finger from engagement with the 105 teeth of the detector, and means actuated on the occurrence of an abnormal condition in the harness mechanism for moving the stop finger into engagement with the toothed detector to arrest its lengthwise movement and 110 effect loom stoppage.

3. In a harness stop mechanism for looms, the combination of shedding mechanism including harness connectors, a detector having teeth, means for impart detecting movements to the detector in the direction of its length, a stop finger mounted for movement into engagement with the toothed detector to arrest its endwise detecting movement and 115 normally held from such engagement until the occurrence of an abnormal condition in a harness connector, and means operated by the abnormally conditioned connector for moving the stop finger into engagement with the toothed detector to arrest its endwise movement and effect loom stoppage. 120

4. In a loom having harness frames and harness connectors, the combination of a warp stop mechanism comprising two relatively lengthwise movable toothed bars and 130

drop wires; a stop finger adapted to engage the toothed bars and lock them from relative lengthwise movement, means for stopping the loom when the toothed bars are locked together, means normally acting to hold the stop finger out of locking engagement with the toothed bars, and means actuated on the occurrence of an abnormal condition in a harness connector for moving the stop finger into locking relation with the toothed bars.

5. In a loom having harness frames and harness connectors, the combination of a warp stop mechanism comprising two relatively lengthwise movable toothed bars and drop wires, a stop finger extending transversely of the toothed bars in normal position to permit their relative lengthwise movement and adapted to engage the toothed bars and lock them from relative lengthwise movement, means for stopping the loom when the toothed bars are locked together, means normally acting to hold the stop finger out of locking engagement with the toothed bars, and means actuated on the occurrence of an abnormal condition in a harness connector for moving the stop finger into locking relation with the toothed bars.

6. In a loom having harness frames and harness connectors, the combination of a warp stop mechanism comprising relatively lengthwise movable detecting members having teeth, a series of drop devices normally supported by the warp threads and adapted to engage the teeth of the detecting members and lock the detecting members together on the occurrence of a warp fault, another drop device adapted to engage the teeth of the detecting members and unsupported by the warp threads but normally held out of locking engagement with the teeth of the lengthwise movable detecting members, means for effecting loom stoppage when the detecting members are locked together, and means operative on the occurrence of an abnormal condition in a harness connector for causing said drop device that is not supported by the warp threads to engage the teeth of the detecting members and lock the detectors from relative lengthwise movement.

7. In a loom, the combination of a plurality of harness frames and harness connectors, detector members having relative movement transversely of the loom and provided with teeth, a series of drop wires normally supported by the warp threads during weaving and acting to engage between the teeth of the detecting members and lock the detectors from relative transverse movement on the occurrence of a warp fault, a drop device normally supported from locking engagement with the teeth of the detectors until the occurrence of an abnormal condition in a harness connection, and means for effecting loom stoppage when the teeth of the

detectors become engaged by either a drop wire or the drop device.

8. In a loom, the combination of a plurality of harness frames and harness connectors, detector members having relative movement transversely of the loom and provided with teeth, yielding means for relatively moving the toothed detectors transversely of the loom, a series of drop wires normally supported by the warp threads during weaving and acting between the teeth of the detectors to lock the detectors from relative transverse movement on the occurrence of a warp fault, a drop device separate from the drop wires and normally supported from locking engagement with the teeth of the detectors until the occurrence of an abnormal condition in a harness connection, and thereupon moved into engagement with the detector teeth to lock the detector, and means for effecting loom stoppage when the relative transverse movement of the detectors is arrested by either a drop wire or the drop device engaging the teeth of the detectors.

9. In a loom, the combination of shedding mechanism including harness frames and harness connectors, toothed detectors having relative movement transversely of the loom, means for stopping the loom when detectors are arrested in their relative movement, a detector stop device normally held out of stopping relation with the toothed detectors until the occurrence of an abnormal condition in one of the harness connectors, and means actuated by an abnormally conditioned harness connector for causing the detector stop device to lock the toothed detectors from relative movement transversely of the loom.

10. In a loom, the combination of shedding mechanism including harness frames and harness connectors, a warp stop mechanism including toothed detectors mounted for relative movement in a direction transversely of the loom, a series of drop wires, means for stopping the loom when a detector is arrested in its relative movement transversely of the loom, a stop finger extending transversely of the toothed detectors, means normally acting to hold the stop finger out of engagement with the toothed detectors, and an actuator for the stop finger rendered operative by a broken or too slack harness connector for moving the stop finger into engagement with the toothed detectors to effect loom stoppage.

11. In a loom, the combination of a plurality of harness frames and harness connectors, a warp stop mechanism including a toothed detector mounted for movement transversely of the loom, means for moving the detector transversely of the loom, means for stopping the loom when the transverse movement of the detector is arrested,

a detector stop member supported to extend transversely of the detector, means normally acting to hold the stop member from engagement with the teeth of the transversely movable detector, an actuator for the stop member, connections between the stop member and actuator rendered effective to move the stop member into engagement with the teeth of the detector by an abnormal condition in a harness connector.

12. In a loom having harness frames and harness connectors, the combination of a plurality of fixed and movable toothed detectors, means for imparting lengthwise movement transversely of the loom to the movable detectors, a stop finger supported

between the ends of the toothed detectors in position to engage between the teeth of the fixed and movable detectors to arrest relative lengthwise movement of the detectors, means acting on the stop finger to normally retain the stop finger out of engagement with the toothed detectors, and an actuator connected to the stop finger and extending beneath the harness connectors to be operated by any slack harness connector to move the finger into engagement with the toothed detectors and stop the loom.

In testimony whereof, I have signed my name to this specification.

GEORGE RHEAULT. [L. s.]
